UNITED STATES PATENT OFFICE.

SAMUEL M. FISCHER, OF NEW YORK, N. Y.

PLACKET-CLASP.

No. 818,823.

Specification of Letters Patent.

Patented April 24, 1906.

Application filed August 19, 1905. Serial No. 274,821.

To all whom it may concern:

Be it known that I, SAMUEL M. FISCHER, a resident of the city of New York, borough of Manhattan, county and State of New York, 5 have invented certain new and useful Improvements in Placket-Clasps, of which the following is a specification.

This invention relates to an improved form of clasp, and is particularly well adapted for 10 usage upon garments where buttons are objectionable or impracticable.

The device as herein illustrated is shown applied to the placket of a skirt, but is not intended to be limited to such limited use.

15 The invention has for its object to provide a simple and inexpensive clasp or fastener of the character mentioned by which easy and secure fastening of garments may be readily effected and yet promptly unfastened when 20 desired.

To these and other ends, which will herein-after appear, my invention comprises the novel features of improvement and combination and arrangement of parts, which I will 25 now proceed to describe and finally claim.

Reference is to be had to the accompanying drawings, forming part hereof, wherein—

Figure 1 illustrates a portion of the back of a skirt, my improved clasp being shown applied to the placket thereof. Fig. 2 is a top plan view of the socket member of the clasp. Fig. 3 is a section thereof, taken on the line *a*—*a* in Fig. 2. Fig. 4 is a side view of the socket member shown in Fig. 2 looking in the direction of the arrow in said figure. Fig. 5 is a bottom plan view of the tongue member of the clasp. Fig. 6 is a section thereof, the section being taken on a line *b*—*b* in Fig. 5; and Fig. 7 is an enlarged view of the socket 35 member and tongue members assembled in locked position, the dotted lines indicating the manner of inserting the tongue member into the socket member.

Like numerals of reference indicate corresponding parts in the several views.

Referring to the drawings, the numeral 1 indicates a portion of a skirt having the usual opening or placket 2 at the back thereof.

3 indicates the socket member of my device, and 11 is the tongue member.

The placket is shown in the drawings partially open to better illustrate my device, there being as many clasps employed as is necessary to hold the placket closed.

55 Referring to Figs. 2, 3, and 4, the socket member 3 is composed of a base 5, an over-

hanging spring-guard 6, and an overhanging resilient leaf or keeper 7 adjacent thereto, the keeper 7 being provided with a socket 8, the under portion of which forms a tongue 8^a. As will be seen from Fig. 4, the keeper 7 is provided with downward projections or wings 9 9 at each end to prevent the premature lengthwise separation of the tongue member therefrom. The base 5 of the socket 65 member 3 is provided with openings 10 for the purpose of attachment. 11 indicates the tongue member of the clasp, which is composed of a base 12, a resilient overhanging leaf or keeper 13, and a spring-guard 14, 70 overhanging said keeper, thus forming a tongue, the keeper 13 being provided with a socket 15 for receiving the tongue 8^a, formed by the socket 8 of the socket member 3. The socket 8 of the member 3 and the socket 15 of 75 the member 11 are formed in the metal when said members are stamped or otherwise formed. The member 11 is secured to the garment in a manner similar to the member 3 and is provided with openings 16 for this purpose. It may here be stated that the member 11, as shown in Fig. 5, is in a position just reverse of the one occupied when applied for coöperation with member 3. When the placket of a skirt or any two or more pieces 80 of material are held together by my improved clasp, said clasp will be in a position illustrated by Fig. 7. When the tongue member 11 is inserted into the socket member 3, the guard 14 of member 11 will press the guard 6 of the 85 member 3 downwardly, as shown by dotted lines in Fig. 7. The tongue member being then forced still farther inwardly will finally assume a position as shown by full lines, at which time the tongue 8^a will have been 90 forced by the resiliency of the material into the socket 15 of member 11. When the tongue and socket members are clasped, the keeper 13 will be between the projections or wings 9 9, as shown by dotted lines in Fig. 2. 100 It has been shown that when the clasp members are locked the respective guards 6 and 14 have been forced past each other until the guard 14 has been completely inserted between the base 5 and keeper 7 of socket member 3, Fig. 7. Consequently the two members cannot be separated laterally, or, in other words, in the reverse direction to the one for locking, as the two guards 6 and 14 would catch and prevent such action, and, as 105 will be seen by Fig. 7, the guard 14, base 5, and keepers 7 and 13 are in contact, the parts

110

being so held by the resiliency of the metal and normally prevented from lengthwise disconnection by the wings 9 9. (See Fig. 2.) There is but one way to disconnect the parts—
5 namely, by slidably forcing them apart lengthwise—that is, pulling member 11 lengthwise from member 3—the keeper 7 being sprung upwardly by such pull when the socket member 3 contacts a wing 9, and thus
10 permitting the tongue member 11 to be withdrawn from the socket member 3, or vice-versa, in a lengthwise direction. The action of the tongue 8^a and socket 15 and wings 9 9 prevent the members constituting the clasp
15 from premature separation; but by a lengthwise pull the members may be separated without difficulty.

When a series of my clasps are applied to the placket of a skirt or to other parts to be
20 detachably connected, the fastening operation can be very easily and promptly accomplished and the parts unfastened even more readily, as it will then simply be necessary to give a direct pull upon either the part of the
25 garment having the tongue or the socket members of the clasp, the pull of course being in a direction lengthwise of said members. Of course it will be understood that the frictional contact and resiliency of the metal constituting
30 the tongue and socket members described is such that under ordinary pressure to which garments provided with my clasps are subjected the parts will not be disconnected, but that it will require a direct abnormal pull
35 or pressure to cause such disconnection.

Having now described my invention, what I claim, and desire to secure by Letters Patent, is—

1. In a clasp, the combination of a socket
40 member, comprising a base, a guard carried by said base and a keeper adjacent to said guard, said keeper being formed by a leaf projecting from said base; a tongue member comprising a base, a tongue formed by a leaf
45 projecting from said base, and a guard carried by said tongue, said guards adapted to prevent lateral separation of said members, and said tongue and socket members being adapted for slidable disconnection.

50 2. In a clasp, the combination of a socket member, comprising a base, a guard carried by said base and a keeper adjacent to said guard, said keeper being formed by a leaf projecting from said base; a tongue member comprising a base, a tongue formed by a leaf projecting from said base, and a guard carried by said tongue, said guards adapted to prevent lateral separation of said members, and said tongue and socket members being
55 adapted for slidable disconnection, together with means adapted to prevent premature separation of said members.

60 3. In a clasp, the combination of a socket member, comprising a base, a guard carried by said base and a keeper adjacent to said

guard, said keeper being formed by a leaf projecting from said base; a tongue member comprising a base, a tongue formed by a leaf projecting from said base, and a guard carried by said tongue, said guards adapted to prevent lateral separation of said members, and said tongue and socket members being adapted for slidable disconnection, together with downwardly-projecting wings carried by the keeper of said socket member adapted to prevent the premature separation of said socket and tongue members.
70 75

4. In a clasp, the combination of a socket member, comprising a base, a guard carried by said base and a keeper adjacent to said guard, said keeper being formed by a leaf projecting from said base; a tongue member comprising a base, a tongue formed by a leaf projecting from said base, and a guard carried by said tongue, said guards adapted to prevent lateral separation of said members, said tongue and socket members being adapted for slidable disconnection, an auxiliary tongue carried by the keeper of said socket member, and an auxiliary socket formed in
80 the tongue of said tongue member, said auxiliary tongue adapted to enter said auxiliary socket when said members are connected.
85

5. In a clasp, the combination of a socket member, comprising a base, a guard carried by said base and a keeper adjacent to said guard, said keeper being formed by a leaf projecting from said base; a tongue member comprising a base, a tongue formed by a leaf projecting from said base, and a guard carried by said tongue, said guards adapted to prevent lateral separation of said members, said tongue and socket members being adapted for slidable disconnection, downwardly-projecting members carried by the keeper of
90 said socket member, adapted to prevent the premature separation of said socket and tongue members, an auxiliary tongue carried by the keeper of said socket member, and an auxiliary socket formed in the tongue of said
95 tongue member, said auxiliary tongue adapted to enter said auxiliary socket when said members are connected.
100

6. In a clasp, the combination of a socket member, comprising a base, a guard carried by said base and a keeper adjacent to said guard, said keeper being formed by a leaf projecting from said base; a tongue member comprising a base, a tongue formed by a leaf projecting from said base, and a guard carried by said tongue, said guards adapted to prevent lateral separation of said members and said tongue and socket members being adapted for slidable disconnection, downwardly-projecting wings carried by the keeper of
105 said socket member, adapted to prevent the premature separation of said tongue members, said downwardly-projecting wings embracing the tongue of said tongue member.
110

7. In a clasp, the combination of a socket
115

member, composed of a base, a resilient guard integral therewith, a resilient keeper formed by a projecting leaf also integral with said base, a tongue member composed of a base, a tongue composed of a projecting leaf integral therewith, and a guard integral with said tongue, said members adapted for lateral connection and slidable separation lengthwise thereof.

10 8. A clasp, consisting of a socket member comprising a base, an overhanging resilient guard and an overhanging keeper, the latter

provided with downwardly-projecting retaining-wings; and a tongue member comprising a base, a resilient overhanging keeper and a resilient guard overhanging said keeper, all arranged so that the said tongue and socket members are adapted for lateral interlocking and lengthwise slidable separation. 15
